HONING MACHINE

Hector R. Berard, Worcester, Mass., assignor to
The Heald Machine Company, Worcester,
Mass., a corporation of Massachusetts

Application November 5, 1936, Serial No. 109,329

10 Claims.

(Cl. 51—92)

The present invention relates to a machine for honing workpieces and is especially directed to a machine by which the pressure exerted by the individual honing members on the workpiece may be varied during the honing operation.

In certain types of honing it is desirable to start the honing operation with the honing members exerting a relatively high pressure on the workpiece, with this pressure being gradually reduced as the honing operation continues in order to produce the desired finish on the surface of the workpiece. The principal object of the present invention is to provide for automatically varying the amount of pressure exerted by the honing members during the honing operation. One particular feature is the provision for reducing the pressure exerted by the honing members as the operation continues, until the members are ultimately withdrawn from the workpiece surface.

Other and further objects and advantages of the invention will hereinafter more fully appear from the following detailed description taken in connection with the accompanying drawing in which the single figure is a side elevation of a honing head embodying the invention, with parts in section, to show certain features, and with parts diagrammatically shown.

Like reference character refer to like parts throughout the drawing.

With reference to the drawing, the machine which discloses one embodiment of the invention has a base 1, on which is mounted, for reciprocation, a table 2, the base being provided with guideways, not shown, on which the table is slideable. A bridge 3 extends over the table at one end of the base. Either the workpiece or the hone may be mounted on the table; in the arrangement shown the bridge carries a honing head 4, and the workpiece 2 is operated upon by the hone 3 is mounted in a suitable work-support 5 secured to the table. The table is shifted by any suitable mechanism, as by the well known fluid pressure actuated mechanism, for procuring a movement of the workpiece into and out of operative position, and if desired, a slight axial reciprocation between the hone and workpiece when the workpiece is in operative position.

The honing head 4 comprises a housing 6, secured to the upper side of the bridge 3, in which is journalled a spindle 7. A hone 8 is mounted on the right hand end of the spindle in a position to engage with the workpiece 2 and is preferably removably positioned on the spindle to permit the substitution of one hone for

another having different honing characteristics. The spindle is rotated by a pulley 9 on the left hand end of the spindle.

The hone disclosed is similar to the hone described and shown in the co-pending Blood application, Serial No. 100,580, filed September 14, 1936, now Blood Patent No. 2,086,660, dated July 13, 1937, although any other similar type of hone can be used. It is sufficient to note for the purposes of the present application that the hone comprises an arbor 10 having an axial bore 11 in which a spindle 12 is slidable, the latter being suitably held against rotation within the arbor. The spindle 12, as shown, is made up of 15 separate elements which are, however, functionally integral and are so described. The arbor 10 has a plurality of radial slots 13 in each of which is positioned a hone carrying lever 14, and an arcuate shoulder 15 on the spindle 12 is engageable with an arcuate protuberance 16 at the corner of each of the levers. A cylindrical hub 17 on the arbor has an internal thread to provide for attachment of the hone to the end of the spindle 7.

Surrounding the arbor at the base of the slots is a ring 18 suitably secured to the arbor. Between the ring and the arbor is clamped a resilient disk 19 in the form of a diaphragm having a plurality of inwardly extending fingers 20, one 25 of which projects inwardly into each of the slots 13.

Each lever 14 has an arcuate lug 21 engageable with the inner or left hand side of the corresponding finger 20 to permit rocking movement of said lever about the lug 21. The opposite end of the lever has an arcuate lug 22 which engages in an arcuate recess 23 in a hone carrier 24. On the outer side of each carrier is a plate 25 to which is secured, as by a suitable adhesive, 30 a honing member, preferably in the form of a stone 26, of abrasive material. The honing stones are additionally held on the carrier plates by flanges 27 extending outwardly from the plates.

The plates 25 are releasably held on the carriers by coil springs 28 and 29, each in the form of an annulus extending around the arbor. The spring 28 is positioned at the inner or left hand end of the plates and engages with the left hand edge of the flanges 27 thereon. The other coil spring 29 is positioned in a recess 30 in the outer end of each of the plates 25, the inturned portion of the plate which forms the recess engaging in a correspondingly shaped recess 31 in the carrier. These coil springs hold the plates on the

carriers and also hold the carriers in engagement with the corresponding levers 14. The levers are held in predetermined relation to each other by a coil spring 32, also in the form of an annulus, positioned in a slot 33 provided in the arbor 10. The spindle 12 has an axially positioned bolt 34 in the end thereof by which to control the effective length of said spindle, the bolt being locked in adjusted position by a clamping nut 35.

For expanding the hone the spindle 7 has an axial bore 36 in which the inner end of the spindle 12 is received. Within the bore 36 is positioned an actuating rod 37 having at the right hand end thereof a plunger 38 engageable with the head of the bolt 34 and the rod is urged to the right by a compression spring 39 surrounding the rod and positioned between the plunger 38 and a collar 40 within the bore. Movement of the rod 37 to the right is limited by a nut 41 on the threaded left hand end of the rod, said nut having a projecting flange engageable with the end of the pulley 9. A second nut 42 on the rod is held against turning movement relative to the nut 41 by a pin 43 extending through both of the nuts, and a coil spring 44 positioned between the nuts and engageable in recesses therein urges the nuts apart to place a frictional drag thereon.

A compensation for wear on the honing stones is provided and this compensatory mechanism may correspond to that disclosed in the copending application of Blood and Schmidt, Serial No. 103,725, filed October 2, 1936, now Patent No. 2,174,029 dated September 26, 1939. By this arrangement, when the stones 28 become worn the nuts 41 and 42 are backed away on the rod to allow a slightly greater expansion of the hone which will compensate for reduction in size thereof. To this end the nut 41 has a collar 45 extending therearound and in a position for engagement with a radial flange 46 on the nut 42. The collar is mounted in an open slot 47 in an arm 48 and is carried on trunnions, not shown, extending inwardly from opposite sides of said slot for turning movement of said collar therein. The arm 48 is journalled on a pin 49 in a bracket 50 secured to the housing 6. A projecting bar 51 forming part of the arm 48 has an adjustable stop 52 engageable with a part of the bracket 50 and an adjustable stop 53 in the bracket is engageable with the bar 51. The cooperating stops 52 and 53 limit the rocking movement of the arm 48 in both directions.

The lower end of the arm 48 has a plunger 54 slidably mounted therein and normally urged into the position shown by a coil spring 55 surrounding the plunger. The movement of the latter to the right is limited by adjusting nuts 56 on the left hand end of said plunger. The plunger is in a position for engagement with the end of the table 2 as the latter reaches operative position and an oscillation of the arm 48 occurs during the reciprocatory movement of the table while in operative position.

In the normal oscillatory movement of the arm 48 the collar 45 does not come in contact with the flange 46 since the latter is moved to the left as the collar moves to the left by the contraction of the hone resulting from movement of the workpiece to the left relative to the stones. As the stones become worn so that a compensation for wear is necessary, the flange 46 is moved less and less to the left during the honing operation until the flange 46 and collar 45 engage

each other with sufficient pressure for the nut 42 to be held against turning movement by the collar, thereby turning the nuts 41 and 42 a slight amount on the rod 37.

5 The above structure is all fully described and claimed in earlier patents and copending applications and does not, of itself, embody the present invention. The latter involves, in connection with the above or similar honing machine 10 elements, the attainment of the objects and novel features above set forth. In accordance with the present invention the hone is expanded against the workpiece by a fluid pressure actuated mechanism supplementing the usual spring 39 and the 15 fluid pressure mechanism is arranged to procure a gradual reduction in the pressure exerted by the stones on the workpiece until the hones are fully withdrawn from engagement with the honed surface.

20 With reference again to the drawing, the nut 42 on the outer end of the rod 37 has an integral flange 57, in which are provided slots for balls 57'. A flanged collar 58 is held against movement relative to the flange 57 by a cap 59 extending over the flange 57 and engaging the balls 57', said cap being in threaded engagement with the collar 58. The collar 58 is secured by a key 60 to a piston rod 61 having at its opposite end a piston 62 slidable in a cylinder 63 in a housing 64 secured to the main housing 6. The piston 62 is normally urged to the left by a heavy coil spring 65 positioned between the piston and a ring 66 surrounding the piston rod at the right hand end of the cylinder. The spring 65 is heavy enough to counteract the effect of the spring 39 and thus normally hold the hone in contracted position.

Fluid under pressure is directed to the left hand end of the cylinder 63 for expanding the hone. To this end, the cylinder 63 has a port 67 at the left hand end which is connected by a conduit 68 to a port 69 in a valve casing 70. A branch conduit 71 provides a connection between the conduit 68 and a port 72 axially spaced from the port 69 in the casing 70. A valve 73, slidable within the valve casing, normally provides a fluid connection between an inlet port 74 in the casing 70 and the port 69 by a reduced portion 75 of the valve, and the same reduced portion connects the port 69 to a port 76 substantially opposite to the port 69. The port 74 is connected to a suitable source of fluid under pressure, not shown, which may be a constant pressure pump.

55 A projecting valve stem 77 on the valve is connected to the armature 78 of a solenoid 79 which is energized at the beginning of the honing operation to hold the valve 73 in the position shown. During the honing operation the valve 73 is shifted to the right under the action of a spring 80 positioned in the casing at the left hand end of the valve. For effecting the shifting of the valve 73 to the right, the circuit through the solenoid is broken during the honing operation by any suitable mechanism, which may be, for example, a mechanism corresponding to the timing elements described in the copending application of Blood and Schmidt, Serial No. 103,725, filed October 2, 1936, above referred to. In any event, the circuit through the solenoid 79 is broken during the honing operation to de-energize the solenoid, thereby allowing movement of the valve 73 to the right, closing the ports 69 and 76 and providing fluid connection between the ports 72 and a port 81 around a second reduced portion 82 of the valve.

The port 76 is connected by a conduit 83 to a port 84 at the left hand end of a casing 85 having a cylindrical bore 86 in which a plunger 87 is slideable. An exhaust port 88 is also provided at the same end of the cylinder 86 and has a throttle valve 89 located therein to control the amount of fluid exhausting from the cylinder. The casing 85 has a second cylindrical bore 90 slightly smaller in diameter than the bore 86 and a valve 91 is located in this bore. A coil spring 92 between the plunger 87 and valve 91 holds the valve 91 in the right hand position shown while the plunger 87 remains in the position shown. Movement of the plunger 87 to the right is limited by engagement with the shoulder 93 at the right hand end of the bore 86.

The valve port 81 in the casing 70 is connected by a conduit 94 to a port 95 in the casing 85 and this port is normally connected by a reduced portion 96 of the valve 91 to an inlet port 97 suitably connected to the same source of pressure to which the port 74 is connected. A bypass conduit 98 provides a connection between the conduit 94 and a port 99 at the right hand end of the valve 91. An exhaust port 100 adjacent the right hand end of the bore 90 in the casing 85 is normally closed by the valve 91 but is opened as the valve moves to the left.

As stated above, the structure for automatic de-energizing of the solenoid 79 during the honing operation may correspond to the timing mechanism disclosed in the Blood and Schmidt application, Serial No. 103,725. To this end the base 1 of the machine may have mounted thereon a timing element 101, of any well known character, which is set in operation as the table 2 moves toward the workpiece by means of a cam 102 which engages the actuating arm 103 of the timer. Timer leads 104 and 105 are connected in series with the solenoid 79 and a suitable source of power, not shown. The timer is adjusted to close the circuit through the solenoid as the table 2 reaches the left hand position shown, with the work in engagement with the hone, and to break the circuit through the solenoid a predetermined time thereafter. The time interval is determined by suitable adjustment of the timer.

In the operation of the machine the table 2 moves to the left into the position shown with a workpiece *a* in engagement with the honing stones. The hone is, however, collapsed between honing operation by the spring 65 which exerts a great enough pressure on the piston 62 to overcome the expanding effect of the spring 39. When the table 2 reaches operative position the solenoid 79 is suitably energized to shift the valve 73 into the position shown for directing fluid under pressure from the port 74 to the port 69 and thence to the left hand end of the cylinder 63, thereby procuring an expansion of the hone to urge the stones into operative engagement with the workpiece surface at a pressure controlled by the pressure of the fluid entering the port 74.

With the valve 73 in this position, fluid under pressure is also directed through the conduit 83 to the casing 85, urging the plunger 87 to the right into the position shown and holding the valve 91 in its right hand position. The amount of fluid escaping past the throttle valve 89 does not affect the pressure on the piston 62 to an appreciable extent.

After the honing operation has continued for a predetermined period the solenoid 79 is suitably de-energized by any automatic mechanism,

thereby allowing the valve 73 to move into its right hand position, cutting off the flow of fluid to the cylinder 63 by way of the port 69, but allowing the admission of fluid under pressure from the valve 89 by way of the ports 81 and 72. When the valve 73 is shifted, fluid under pressure to the cylinder bore 86 is cut off and, as fluid continues to exhaust from this bore through the port 88 the plunger 87 is gradually moved to the left by the spring 92. The fluid under pressure entering the port 99 at the right of the valve 91 ultimately overcomes the holding action of the spring 92 and the plunger 87, thereby effecting a movement of the valve 91 to the left to open the exhaust port 100 and thus allow the gradual escape of fluid under pressure from the cylinder 63. As the valve 91 moves to the left the port 95 is at least partially closed to throttle the amount of fluid under pressure passing around the valve 91 and entering the conduit 94, so that all this fluid and that in the cylinder 62 may gradually exhaust through the port 100. The fluid pressure in the cylinder 63 is thus gradually diminished as the exhaust port 100 is opened more and more so that the pressure exerted by the honing stones on the workpiece is similarly reduced until the stones are finally withdrawn from engagement with the workpiece by the action of the spring 65.

From the foregoing it will be apparent that the present invention provides for an automatic change in the pressure exerted on the workpiece by the honing stones. In the particular embodiment of the invention described above, this change in the amount of pressure comprises a gradual reduction in the pressure exerted by the stones so that the stones exert less and less pressure during the honing operation until the stones are completely withdrawn from engagement with the workpiece.

I claim:

1. In a honing device, a hone arbor, at least one honing member movable relative thereto, means for urging said member into operative position relative to the arbor for engagement with a workpiece, and means automatically operative during a honing operation for procuring a gradual reduction in the pressure exerted by the member on the workpiece without varying the operative position of the member, and subsequently a retraction of the member from operative engagement with the workpiece, said last means being controlled by fluid under pressure.

2. In a honing device, a hone arbor, a honing member movable relative thereto, fluid pressure actuated means for procuring a movement of said member into operative relation to a workpiece, and automatically operative means for procuring a gradual reduction in the pressure exerted by said member on the workpiece when in operative position.

3. In a honing device, a hone arbor, a honing member movable relative thereto, an actuating rod for said member, fluid pressure actuated means for urging said member into operative relation to a workpiece, and automatically operative means for procuring a gradual variation in the fluid pressure in said means for changing the pressure exerted by the member on a workpiece without varying the operative position of the honing member.

4. In a honing device, a hone arbor, a honing member movable relative thereto, an actuating rod for said member, fluid pressure actuated means for moving said rod in one direction, re-

silient means for urging said rod in the opposite direction, and means for automatically varying the fluid pressure in said fluid pressure actuated means without varying the operative position of the honing member.

5. In a honing device, a hone arbor, a honing member movable relative thereto, an actuating rod for said member, fluid pressure actuated means for moving said rod in one direction, resilient means for urging said rod in the opposite direction, and means for automatically varying the fluid pressure in said fluid pressure actuated means during a honing operation for varying the pressure between the member and a workpiece without varying the operative position of the member relative to the arbor.

6. In a honing device, a hone arbor, a honing member movable relative thereto, an actuating rod for said member, fluid pressure actuated means for moving said rod in a direction to move the member into operative position, resilient means for urging said rod in the opposite direction, and means for controlling the action of the fluid pressure actuated means for procuring a gradual change in the pressure exerted by the member against a workpiece without varying the operative position of the member relative to the arbor.

7. In a honing device, a hone arbor, at least one honing member movable relative thereto, and fluid pressure controlled means for urging said member into operative relation to a workpiece with a varying pressure during a honing operation without varying the position of said member relative to the arbor, said fluid pressure controlled means also procuring an automatic retraction of the honing member from operative position at the end of the honing operation.

8. In a honing device a head, a spindle journaled in the head, a hone mounted on one end of the spindle, said hone comprising an arbor, at least one lever mounted in the arbor for rocking movement relative thereto and a honing member carried by said lever, a plunger axially slidable in the spindle, said plunger by axial movement procuring movement of the honing member relative to the arbor into and out of operative position, resilient means engageable with the plunger

to urge said plunger axially in one direction, fluid pressure means associated with the plunger to move said plunger in the opposite direction and means to provide for gradual reduction in the pressure of the fluid in said fluid pressure means for varying the pressure exerted by said fluid pressure means on the plunger.

9. In a honing device a head, a spindle journaled in the head, a hone mounted on one of the spindle, said hone comprising an arbor, at least one lever mounted in the arbor for rocking movement relative thereto and a honing member carried by said lever, a plunger axially slidable in the spindle, said plunger by axial movement procuring movement of the honing member relative to the arbor into and out of operative position, resilient means engageable with the plunger to urge said plunger axially in one direction, fluid pressure means associated with the plunger to move said plunger in the opposite direction, said fluid pressure means including a piston and cylinder, one of which is connected to the plunger, means for directing fluid under pressure to said cylinder for movement of the plunger in one direction, and means to provide for a gradual reduction in the pressure of the fluid in the cylinder for a gradual reduction in the pressure exerted by the honing member against a workpiece.

10. In a honing device a head, a spindle journaled in the head, a hone mounted on one end of the spindle, said hone comprising an arbor, at least one lever mounted in the arbor for rocking movement relative thereto and a honing member carried by said lever, a plunger axially slidable in the spindle, said plunger by axial movement procuring movement of the honing member relative to the arbor into and out of operative position, resilient means engageable with the plunger to urge said plunger axially in one direction, fluid pressure means associated with the plunger to move said plunger in the opposite direction, means for limiting the movement of the plunger in one direction, thereby determining the operative position of the honing member, and means for automatically adjusting said limiting means to compensate for wear on the honing member.
